Primary Examiner — Cynthia Ramirez*Assistant Examiner* — Gino Colan(74) *Attorney, Agent, or Firm* — Erickson Kernell IP, LLC(57) **CLAIM**

The ornamental design for a fuel pressure regulator, as shown and described.

DESCRIPTION

FIG. 1 is a perspective view of a fuel pressure regulator showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the figures are included for the purpose of illustrating portions of the fuel pressure regulator and form no part of the claimed design.
